CLAIM

The ornamental design for lab scanner as shown and described.

DESCRIPTION

FIG. 1 is a front isometric view of a lab scanner.

FIG. 2 is a front side elevation view thereof.

FIG. 3 is a back side elevation view thereof.

FIG. 4 is a left side elevation view thereof

FIG. 5 is a right side elevation view thereof.

FIG. 6 is a top plan view thereof.

FIG. 7 is a bottom plan view thereof.

FIG. 8 is a front isometric view of FIG. 1 with the only difference being the scanner arm is in a different location, it being understood that all other surfaces are the same as the other views of this embodiment.

FIG. 9 is a front isometric view of FIG. 1 with the only difference being the scanner arm is in a different location, it being understood that all other surfaces are the same as the other views of this embodiment; and,

FIG. 10 is a back isometric view of FIG. 1

The features shown in broken lines in the drawing depict environmental subject matter only and form no part of the claimed design.
